(57) **CLAIM**

The ornamental design for a mount for an indicator or instrument, as shown and described.

DESCRIPTION

FIG. 1 is a perspective view of a mount for an indicator or instrument showing my new design;

FIG. 2 is a right side elevational view of the mount for an indicator or instrument of FIG. 1;

FIG. 3 is a left side elevational view of the mount for an indicator or instrument of FIG. 1;

FIG. 4 is a bottom plan view of the mount for an indicator or instrument of FIG. 1;

FIG. 5 is a top plan view of the mount for an indicator or instrument of FIG. 1;

FIG. 6 is a front side elevational view of the mount for an indicator or instrument of FIG. 1; and,

FIG. 7 is a rear side elevational view of the mount for an indicator or instrument of FIG. 1.

The broken lines shown in the drawings illustrate portions of the mount for an indicator or instrument that form no part of the claimed design.
